UNITED STATES PATENT OFFICE.

PAUL KURTZ, OF MARSHALLTOWN, IOWA.

DESIGN FOR A FURNITURE-CASE.

SPECIFICATION forming part of Design No. 22,100, dated January 3, 1893.

Application filed November 9, 1892. Serial No. 451,464. Term of patent 3½ years.

To all whom it may concern:

Be it known that I, PAUL KURTZ, residing at Marshalltown, in the county of Marshall and State of Iowa, have invented and produced a new and original Design for a Furniture-Case, of which the following is a specification.

The figure is an isometric view of a furniture case embodying my design.

My invention consists of an ornamental design for furniture cases such as are framed or boxed in with closed sides.

The leading feature of the design is the corner piece in which the sharp angle of the corner is replaced by a curved panel that is sunken within the planes of the two adjacent sides, and which curved surface is ornamented with carving spread longitudinally along

such curved sunken panel. A B represent the two sides of the case, which occupy planes at right angles to each other. Between the two sides and occupying a position within the angle that would be formed by the extension of the two sides is the sunken curved surface C, which bears ornamental carving spread longitudinally along the panel. This gives a very ornamental and pleasing effect—

Having thus described my invention, what I claim is

The design for a furniture case as herein shown and described.

PAUL KURTZ.
